C. BUTLER.

DIPPER FOR STEAM SHOVELS AND DRÉGES.

APPLICATION FILED FEB. 27, 1913.

1,076,548.

Patented Oct. 21, 1913.

UNITED STATES PATENT OFFICE.

COOLEY BUTLER, OF NEW YORK, N. Y.

DIPPER FOR STEAM SHOVELS AND DREDGES.

1,076,548.

Specification of Letters Patent.

Patented Oct. 21, 1913.

Application filed February 27, 1913. Serial No. 750,988.

To all whom it may concern:

Be it known that I, COOLEY BUTLER, a citizen of the United States, and a resident of the city of New York, borough of Manhattan, in the county and State of New York, have invented a new and Improved Dipper for Steam Shovels and Dredges, of which the following is a full, clear, and exact description.

This invention relates to excavating or dredging machinery and has particular reference to certain details of construction in dippers.

The primary object of the invention is to improve the form of teeth as to the means for securing them to the cutting edge or front of the dipper.

Another object of the invention is to improve the locking means for the door.

The foregoing and other objects of the invention will hereinafter be more fully described and claimed and illustrated in the drawings forming a part of this specification, in which like characters of reference indicate corresponding parts in all the views, and in which—

Figure 1 is a perspective view illustrating a dipper having my improvements embodied therein; Fig. 2 is a plan view of the same, one tooth being omitted; Fig. 3 is a vertical sectional view on the line 3—3 of Fig. 2; and Fig. 4 is a similar view on the line 4—4 of Fig. 2.

The several parts of this dipper may be made of any suitable materials, and the relative sizes and proportions thereof may be varied somewhat from those illustrated without departing from the spirit of the invention hereinafter claimed.

As shown, the dipper comprises as usual a front 10, a back 11, a door 12, and a bail 13. The front and back are connected along the sides by a series of rivets or the like 14. The door is connected to the back by the usual hinges 15 pivoted to the back in a well known manner. The bail is connected to the body of the dipper by means of pivots 16 extending outwardly through the bail and brackets 17. At the lower end of the front of the dipper is a projection 18 having a hole 18' therethrough, and the ends of the said projection, extending laterally toward the sides of the dipper, are beveled as shown at 19, said beveled portions extending well outward toward said sides. A locking bolt

20 movable on the outside of the door as usual is adapted to operate in said hole 18' to lock the door closed. This special form of construction at 18 provides greater strength than usual, and at the same time 66 eliminates the part that is commonly called a latch plate, and the rivets securing it to the dippers now commonly in use.

As has heretofore been done, the teeth 21 are made removable from the front of the dipper for the purposes of repair or replacement. In this connection each tooth comprises inner and outer fingers 22 and 23, said fingers embracing the inner and outer surfaces of the lip portion of the dipper 70 front. The tooth is locked to the dipper body in a rigid manner but with the least possible number of removable parts. The main securing means for such tooth comprises a pair of flanges 24 which embrace 75 the inner finger 22, said flanges being undercut or dove-tailed as shown especially in Fig. 2, and a corresponding pair of flanges 25 embracing the outer finger. The flanges 25 are connected by a rib 25' which constitutes a substantial abutment for the tooth in addition to the edge of the dipper front. The cutting edge also of the front portion of the dipper is preferably notched, as shown at 26, to receive the body of each 85 tooth. The notch 26 and the pairs of flanges 24 and 25 on the opposite sides of the body structure provide a substantial support for the tooth with respect to its digging operations. In view, therefore, of the supporting means indicated there is required very little additional means to secure each tooth in place, as compared with structures of this character as ordinarily made. At 27 I show

90 a removable fastener in the nature of a bolt or pin passing through the dipper front and through one finger 22 of the tooth. The bolt 27 is shown provided with a nut 28 to hold it in place. The dipper front and the body of the finger through which this bolt or pin 95 passes are formed as shown so that the bolt or pin may be secured in its place from either the inside or the outside of the dipper. This bolt serves to retain the tooth in place as indicated in Fig. 3. When, however, it is required to renew a tooth, all that is necessary is to remove the bolt and slip the tooth out of place, when a new tooth may be inserted and secured as before, a process requiring but a small fraction of the 100 105 110

amount of time usually spent in removing teeth in dippers where many rivets or the like are used to secure the teeth in place.

Having thus described my invention, I claim as new and desire to secure by Letters Patent:

1. The herein described dipper comprising a body having an edge notch and pairs of undercut flanges formed integrally on the inside and outside of the body structure, a tooth fitted to the dipper body in said notch and having fingers with beveled edges extending between the respective pairs of flanges and interlocking therewith, and a detachable member passing through the dipper body and a portion of said tooth, substantially as and for the purposes set forth.
2. In a dipper, the combination of a dipper body having a front provided adjacent its cutting edge with a series of notches and

pairs of undercut integral flanges adjacent said notches on the inside and outside thereof, a series of detachable teeth, each tooth adapted to be seated in a notch having a pair of fingers and embraced by said pairs of flanges, one pair of flanges having a transverse connecting rib serving as an abutment for one of the fingers, and a single removable member coöperating with the other finger and said body front serving to prevent outward longitudinal displacement of such tooth.

In testimony whereof I have signed my name to this specification in the presence of two subscribing witnesses.

COOLEY BUTLER.

Witnesses:

GEO. L. BEELER,
HARRY SCHROEDER.
